UNITED STATES PATENT OFFICE.

JOSEPH H. COULTER, OF PITTSFIELD, MASSACHUSETTS.

SHUTTLE.

1,360,185.

Specification of Letters Patent. Patented Nov. 23, 1920.

Application filed May 12, 1920. Serial No. 380,771.

To all whom it may concern:

Be it known that I, JOSEPH H. COULTER, a citizen of the United States, residing at Pittsfield, in the county of Berkshire and State of Massachusetts, have invented certain new and useful Improvements in Shuttles, of which the following is a specification.

This invention relates to shuttles; and it comprises a shuttle having the usual pivoted spindle, a spring for maintaining the spindle under tension, the spring being arranged in an opening or cut-out portion in the shuttle, said cut-out portion being provided with a metal lining, the metal lining projecting beyond the opening or cut-out portions and surrounding the spindle pivot, the spindle pivot being mounted in a metallic bushing in the shuttle body, means for relieving the tension on the spindle to facilitate withdrawal and replacement of the spindle, and cushioning means carried by the shuttle and engaging the butt of the spindle.

In the present invention, I have provided improved means for supporting the spring by means of which the spindle is maintained under tension. The provision of a metal bearing plate for the spring removes all strain from the spindle spring and eliminates wearing on the wooden portion of the shuttle. The spindle pivot is mounted in a metallic bushing which furnishes a larger bearing surface and prolongs the life of the shuttle by eliminating wearing on the body portion of the shuttle adjacent the pin.

Cushioning means are arranged in the body portion of the shuttle adjacent the heel of the spindle whereby shocks incidental to manipulation of the spindle when bobbins or tubes are being inserted or removed, are taken up and wear on the wooden portion of the shuttle is minimized.

In the present invention, I have further provided means whereby the tension on the spindle may be removed when a spindle is to be replaced permitting ready removal and replacement of the spindle. Heretofore, it has been very difficult to remove and replace the spindle, due to the pressure of the spring bearing against it.

In the accompanying drawings, I have shown an advantageous embodiment of the invention. In this showing:

Figure 1 is a central vertical sectional view of the invention,

Fig. 2 is a horizontal sectional view at right angles to Fig. 1,

Fig. 3 is an enlarged vertical sectional view of the base of the shuttle, showing the invention in detail,

Fig. 4 is a transverse vertical sectional view on line 4-4 of Fig. 1, and,

Fig. 5 is a detail perspective view of the bearing plate.

65

Referring to the drawings, the reference numeral 1 designates a shuttle of the usual construction, having a pivoted spindle 2. The spindle is pivoted in an opening formed in the body portion of the shuttle and this opening is provided with a metal bushing to minimize wear of the wooden portion of the shuttle surrounding the pivot. As shown, the bushing is made in two portions 3 and 4 and arranged on each side of the spindle. The section 4 of the spindle is made larger than the section 3 and is provided with internal screw-threads. A pivot pin 5 is arranged in the bushings and passes through the usual opening in the spindle. As shown, the pin is provided with threads 6, adapted to engage the internal threads of the bushing 4 and hold it in position. The head of the pin may be slotted, as at 7, to permit its removal with a screw driver or other suitable tool.

The body portion of the shuttle is provided with a recess 8 and a bearing plate 9 is arranged in the recess. This plate is preferably made of metal and, as shown, it is substantially U-shaped and extends outwardly beyond the end of the recess. Elongated slots 10 are arranged in the bearing plate and are adapted to receive the pivot pin. The elongated slots are provided to permit longitudinal adjustment of the bearing plate, when the pressure on the spindle is removed. The spindle is maintained under pressure by coil spring 11, arranged in the recess and bearing against the bottom 12 of the U-shaped plate. A plunger 13 is arranged in the outer end of the coil spring and is provided with a head 14, adapted to engage the end of the spindle and maintain it under tension in the usual manner.

100
105
110
Means are provided for cushioning the heel of the spindle and prevent it from engaging the wooden portion of the shuttle when the spindle is opened and closed. As shown, the body portion of the spindle is provided with a second recess 15 in which is arranged a metal tube 16. A plunger 17

- is mounted within the tube and is surrounded by a coil spring 18, the coil spring serving to hold the plunger head 19 in position. The outer end of the metal tube is 5 provided with projections or lugs 20 to hold the spring in proper position. A cushion block of rubber or other resilient material 21 is arranged between the head of the plunger and the body portion of the spindle.
- 10 By the provision of the spring construction shown, the head 19 is held in proper position in engagement with the cushion block 21. When the cushion block becomes worn, or for any other reason the operator desires 15 to place more cushioning material under the head of the plunger, the plunger may be moved outwardly against the tension of the spring, as shown in Fig. 3, and additional cushioning members placed in position.
- 20 The head of the plunger is provided with two or more pins 19' which serve to maintain the plunger in proper position with respect to the packing.
- To permit ready insertion of the spindle, 25 I have provided means for relieving the tension of the spring 11 when the spindle is to be removed or replaced. In Fig. 1 of the drawings, the spindle is shown under tension, whereas in Fig. 2, the tension of the 30 spring is removed. For this purpose, the depth of the recess 8 is made greater than is necessary for the reception of the spring when the spring is under tension. A transverse slot 22 is arranged at the back of the recess and is adapted to receive a pin 23, 35 whereby the bearing plate is moved forwardly to hold the spring 11 under tension. Any suitable means (not shown) may be employed to maintain the pin 23 in position.
- 40 When the pin is removed and the bearing plate assumes the position in Fig. 2 of the drawings, the tension on the spindle is removed and the spindle may be readily removed or replaced. As shown, one wall 24

of the transverse slot may be inclined to 45 permit free insertion of the pin and the corners of the bearing plate may be slightly rounded, as at 25.

It is to be understood that the form of my invention herewith shown and described is 50 to be taken as a preferred example of the same and that various changes in the shape, size, and arrangement of parts may be resorted to without departing from the spirit of the invention or the scope of the sub- 55 joined claims.

Having thus described my invention, I claim:

1. A shuttle comprising a body portion, a spindle pivotally mounted therein, the body portion being provided with a recess near 60 said spindle pivot, a substantially U-shaped bearing plate arranged in said recess, a spring disposed within the bearing plate, a plunger arranged on the outer end of the 65 spring, said plunger being adapted to engage the spindle to maintain it under tension, and means for relieving the tension on said spindle.

2. A shuttle comprising a body portion, a 70 spindle pivotally mounted therein, the body portion being provided with a recess near said spindle pivot, a substantially U-shaped bearing plate arranged in said recess, said bearing plate extending outwardly beyond 75 the spindle pivot, and being provided with elongated openings for the passage of the pivot, said bearing plate being movable rearwardly to relieve the tension on said spindle, and means for maintaining it in forward 80 position.

In testimony whereof I affix my signature in presence of two witnesses.

JOSEPH H. COULTER.
